UNITED STATES PATENT OFFICE.

PAUL DOBLER, OF MUNICH, GERMANY, ASSIGNOR TO HERR LUDWIG BÖHM, OF MUNICH, GERMANY.

DEVICE FOR AUTOMATICALLY HOLDING DOORS, WINDOWS, &c.

1,098,894.

Specification of Letters Patent.

Patented June 2, 1914.

Application filed September 12, 1913. Serial No. 789,425.

To all whom it may concern:

Be it known that I, PAUL DOBLER, a subject of the German Emperor, residing at Munich, in Germany, have invented certain new and useful Improvements in Devices for Automatically Holding Doors, Windows, &c., of which the following is a specification.

The invention relates to improvements in devices for automatically holding members for closing openings, such as sliding windows, doors and the like, in their end positions or any desired intermediate position. In such devices it is known to provide the edges of the movable member and a corresponding guide part of the opening, with brush-like strips, so that the friction of these strips engaging each other longitudinally provides a braking action which holds the movable member in the desired position.

In the accompanying drawings, Figures 1 and 2 illustrate the known application of frictional coating brushes to a sliding window and door respectively. Figs. 3 to 10 illustrate the improvements of the present invention in which Fig. 3 is a diagram illustrating the principle of the invention. Fig. 4 is an elevation illustrating the bristles of the members out of engagement with the bristles of the other. Fig. 5 is a similar view showing the same in engagement. Fig. 6 is a side elevation of Fig. 4 and illustrates means for adjusting the depth of engagement of the bristles. Fig. 7 is a section on line A—B of Fig. 6. Figs. 8 to 10 illustrate the invention applied to a swing door, Fig. 8 being a cross section through the door post, Fig. 9 a section on line C—D of Fig. 8 and Fig. 10 a diagram.

Referring to Figs. 1 and 2, Fig. 1 shows a sliding window, as used in railway carriages, tramway cars and the like, provided with the known fastening arrangement. Fixed to the vertical edges of the window frame 2 are brushes 3, which extend the whole length of the window and face brushes 5 secured to the guide-bars 4. These brushes, which may be made of steel wire, horse hair or any other suitable material, and may be of various lengths, can be secured with their backs to the window frame and to the window guides by means of screws or the like. The bristles of the facing brushes engage into each other to such a depth that the resultant friction balances the weight of the window, so that the latter is held solely by friction in its

closed or any desired intermediate position. When applied to sliding doors, the brush covers also serve to hold the door in any desired position in addition to its closed position. Fig. 2 shows by way of example the sliding door of a railway carriage provided with this arrangement. As shown, the door 9 is provided along its upper edge with a brush 3 which faces a brush, or a short piece 5 of a brush as shown on the top of the door frame 10. When the door is closed the brushes engaging with each other hold the door in this position without the aid of a catch.

The object of the present invention is to provide an improved form of one of the brush members, the essential feature of which is that it is so arranged that when moved in one direction, it moves out of engagement with its co-operative brush, but engages with the latter when moved in the other direction. When the brushes are in the form of strips, the bristle tufts of one of the brush strips are preferably fixed to rotatable pins arranged transversely to the direction of movement of the window, so that when the movable member is moved in one direction (to close the window) its bristles are turned out of engagement with the bristles of the other brush strip and lie at an acute angle to this direction of movement, but are turned into engagement again when the movable member is moved in the opposite direction (opening the window), whereby at first only the tips of the bristles engage and then gradually assume their fully engaged position. This action is shown diagrammatically in Fig. 3. The tufts of bristles *a* of the brush strip 5 are fixed to rotatable pins *b* mounted transversely to the direction of movement of the brush strip 3, the bristles *a* being inclined so that their lower points rest against the bristles *c* of the brush strip 3. If the brush strip 3 is moved downward in the direction indicated by the arrow, first of all its bristles will engage the tips of the brush tufts *a* and the latter will be turned about the axes of the pins *b*. Hence the bristles of the two brush members will not all engage simultaneously but progressively until they are all in their engaging positions, the depth of engagement being indicated in the drawing by *w*. In order to limit the movement of the bristle tufts *a*, the pins *b* are provided with projec-

tions *d* adapted to abut against a stop *e*. When the brush-strip *3* is moved in the opposite direction to that indicated by the arrow, the bristle tufts *a* are automatically moved out of their positions of engagement, so that the movable member, as for instance a window, can be readily closed, force only being required to open it.

Referring to Figs. 4-7 which illustrate a practical application of the invention, the pins *b* with the tufts of bristles *a* are rotatably mounted between plates *g* and *h* (Fig. 7), held a certain distance apart by pins *f*. The one end of each pin *b* is half cut away so that a semi-circular projection *i* projecting beyond the plate *g* is formed. Arranged around the supports *g*, *h*, *f* for the pins *b* carrying the tufts *a* is an angle piece *k*, against the upper flange of which the flat surface of the projections *i* abut when the brushes *a* are in the position shown in Fig. 4, that is to say, when the window carrying the brush strips *3* is pushed up. The one member of the angle plate *k* serves for securing the brush strip *5* to the guide-bar *4* for the window, and said flange is also provided with inwardly projecting pins *m*, which project through the pins *f* and thus provide a guide for lateral movement of the supporting member *g*, *h*, *f*. This lateral movement occurs when in moving the window downward the bristles of the brush strip *3* engage the tips of the bristle tufts *a*, thereby causing the pins *b* to rotate. During this rotation of the pins *b* the lower edges of the projections *i* abut against the longitudinal edge of the horizontal flange of the angle piece *k* and thus push the whole support for the brush pins to the right, the extent of this displacement being shown by the distance *y* in Fig. 5, whereby the bristles engage to the depth as indicated in Fig. 3. The whole depth of engagement in this case is thus *x+y*. In order to limit the distance *y*, a strip-shaped stop *n* is provided on a plate *o* (Fig. 7), said stop limiting the rotation of the projections *i* and consequently the displacement of the carrier for the brush pins *b*. In order to be able to regulate the distance *y* the plate *o* is adjustably mounted as shown at Fig. 6. For this purpose the flange *k¹* of the plate *k* is provided with two bolts *p* which project through parallel slots *q* in the plate *o*. The flange of the angle-piece *k* is also provided with a pin *r* in which is screwed a stud *s*, the latter abutting at both ends against the horizontal edges of a recess *t* in the plate *o*. The plate *o* is caused to rise or descend by correspondingly turning the stud *s* said plate being simultaneously moved laterally by the guide pins *p* and slots *q*. Nuts *u* serve to lock the plate in its adjusted position.

Figs. 8 and 9 show the arrangement of the rotatable brush pins applied to a swing door

for the purpose of braking the door as it swings to and fro, to avoid slamming which is inseparable with door provided with locks, and to prevent shaking of vehicle doors. Fig. 8 is a cross section through the door post 70 33 and door 34, the braking device 35 being shown in plan, and Fig. 9 is a section on the line C—D of Fig. 8. The parts *g¹*, *h¹*, *f¹*, *n¹* correspond in these figures with the parts *g*, *h*, *f*, *n* of Figs. 4-7. *f¹* is a web connecting the plates *g¹*, *h¹* and by which the device is connected to the door-post 33. Two separate rows of brush-pins are provided in this case, one on either side of the center line of the door-post, and the pins with the bristles thereon are arranged to turn at an angle toward the door as clearly shown in the drawing, a space remaining between the two sets for the brush strip on the edge of the swing door 34. When the door is opened in the direction indicated by the arrow (Fig. 8), the brushes on the left-hand side are turned back so that they point straight out and the door can be opened by overcoming the resistance offered thereby. When the door swings 90 back the brushes are forced back into the oblique position as shown, and the door then encountering the resistance offered by the brushes *a* on the right is forced back to its closed position. The movement of the tufts of bristles *a* is limited by the edges of the projections *i* abutting against the plate *n¹*. *w¹* designates the depth of engagement of the brushes *a* and *c*.

What I claim as my invention and desire to secure by Letters Patent of the United States is:—

1. Means for braking the movement of a movable member with respect to a fixed member comprising in combination series of fixed friction members attached to one of said members and a series of pivoted friction members mounted on the other of said members and adapted to turn into or out of engagement with said fixed friction members by the movement of said movable member.

2. Means for braking the movement of a movable member with respect to a fixed member comprising in combination a brush member attached to one of said members and a series of pivoted bristle tufts mounted on the other of said members and adapted to turn into or out of engagement with said brush member by the movement of said movable member.

3. Means for braking the movement of a movable member with respect to a fixed member comprising in combination a brush member attached to one of said members, a series of rotatable pins arranged on said movable member transversely to the direction of movement thereof, bristle tufts mounted on said pins, said tufts being adapted to be turned into or out of engagement with the

bristles of said brush member by the movement of said movable member, means for limiting the rotary movement of said pins allowing lateral movement of said tufts toward said brush member and means for adjusting the depth of engagement between said bristle tufts and the bristles of said brush member.

4. Means for braking the movement of a movable member with respect to a fixed member comprising a brush strip attached to one of said members, a plate attached to the other of said members, a flange thereon, a pair of longitudinal supports spaced apart, 15 rotatable pins mounted between said sup-

ports, bristle tufts mounted on said pins adapted to engage with said brush strip, means carried by said pins and coacting with said flange for causing lateral movement of said supports and the tufts carried thereby 20 with respect to said plate, a stop for limiting said lateral movement, and means for adjusting the position of said stop.

In witness whereof I have signed this specification in the presence of two witnesses.

PAUL DOBLER.
